MEDICAL SUCTION INSTRUMENT TIP

Charles A. Lahay, Fayette, Ala., assignor to
Dart Industries Inc., Los Angeles, Calif.

Filed Feb. 6, 1975, Ser. No. 547,515

Term of patent 14 years

Int. Cl. D24—02, 04

U.S. Cl. D83—12 A

FIG. 1 is a side elevation of a medical suction instrument tip showing my new design, the broken lines shown for illustrative purposes only;

FIG. 2 is an enlarged perspective view of the medical suction instrument tip;

FIG. 3 is an enlarged side elevational view thereof;

FIG. 4 is a rear view thereof;

FIG. 5 is a front view thereof; and

FIG. 6 is a cross sectional view thereof taken along line 6—6 of FIG. 5.

I claim:

The ornamental design for a medical suction instrument tip, substantially as shown and described.
